UNITED STATES PATENT OFFICE

156,378

PHONOGRAPH CABINET

Thomas A. Schwartz, Topeka, Kans.

Application November 29, 1948, Serial No. 149,867

Term of patent 3½ years

(Cl. D56—4)

To all whom it may concern:

Be it known that I, Thomas A. Schwartz, a citizen of the United States, residing at Topeka, in the county of Shawnee and State of Kansas, have invented a new, original, and ornamental Design for a Phonograph Cabinet, of which the following is a specification, reference being had to the accompanying drawing, forming a part thereof.

Fig. 1 is a perspective view of a phonograph cabinet, showing my new design.

Fig. 2 is a side elevational view thereof, the other side being the same.

I claim:

The ornamental design for a phonograph cabinet, as shown and described.

THOMAS A. SCHWARTZ.
